UNITED STATES PATENT OFFICE

ALBION M. ROUSE, OF BOULDER, COLORADO.

MACHINE FOR REDUCING ORES.

SPECIFICATION forming part of Letters Patent No. 350,563, dated October 12, 1886.

Application filed November 11, 1885. Serial No. 182,441. (No model.)

To all whom it may concern:

Be it known that I, ALBION M. ROUSE, of the city and county of Boulder, in the State of Colorado, have invented a certain new and 5 useful Improvement in Machines for Reducing Ores, of which the following is a full, clear, and exact description, reference being had to the accompanying drawings, forming part of this specification.

10 In the machine suspended rollers roll around within an encircling-ring, toward which they are pressed by springs aided by centrifugal force.

The machine is suited for reducing ore 15 either dry or wet, and works upon material that has been broken fine enough to pass through a mesh about one-quarter of an inch in size.

The details of the invention are indicated in the claims.

20 Figure I is a side elevation of the machine, with part broken away and the cap or top and hopper removed. Fig. II is a top view of the parts of the machine shown in Fig. I. Fig. III is a section of the case, &c., at III III, 25 Fig. II, with parts in elevation. Fig. IV is a section at IV IV, Fig. VIII. Fig. V is a section at V V, Fig. VI. Fig. VI is a section at VI VI, Fig. V. Fig. VII is a top view of the working-disk. Fig. VIII is a transverse section of the machine at VIII VIII, Fig. II, in its form for working dry ore, the pulley-shaft, &c., being absent. Fig. IX is a bottom view 30 of a part of the cap.

1 is the base-plate, supported by legs 2 on a 35 bed-plate, 3.

4 and 5 are standards giving bearing to the drive shaft 6, upon which are tight and loose pulleys 7 and 8. On the shaft 6 is a bevel-wheel, 9, engaging a bevel-wheel, 10, upon the 40 vertical shaft 11, to which is keyed the working-disk 12. The shaft 11 is stepped on the standard 5, and rests on a bronze or other disk, 13.

14 is the coned center of the base-plate 1, 45 upon which the working-disk 12 has bearing, the cone 14 having in top an annular groove, which receives an annular boss, 15, upon the bottom of the working-disk.

16 is a ring of bronze or other suitable material, upon which the bottom of the annular 50 boss 15 bears. This bearing is oiled by means

of a pipe, 17, set in the top of the shaft 11 and communicating by an oil-hole with the bearing. (See Fig. VIII.)

18 is a cap on the pipe 17.

19 is an annular flange extending from the bottom of the working-disk downward around the outside of the cone 14, so as to prevent grit getting into the bearing between the working-disk and the cone.

20 is the circular wall of the case, bolted to the base 1, and standing out at 21 to form an annular hopper.

The wall 20 is made in sections connected by flange-joints at 22. (See Figs. I, II.) The 65 wall has apertures 23, which may be covered by gauze or other screens, 24, (see Figs. I, II, and III,) or by plates, (see Fig. VIII,) as hereinafter explained.

25 is the hub of the driving-disk 12, forming a boss upon which the annular hopper 26 has bearing, the hopper turning with the disk.

27 are hollow legs in the hopper, which are set in holes 28 of the disk, and through them the material to be reduced passes from the 75 hopper into the interior of the machine. The material may be fed into the hopper in any desired manner.

29 is a die-ring of hard metal, such as steel or chilled iron, against which the reducing- 80 rollers work.

30 is the annular deflecting-wall above the die-ring. The reducing-rollers are supported upon arms 31, which are hinged to the working-disk by pins 32, which pass through the 85 arms and through holes 33 in the working-disk.

34 are keys passing through mortises in the tops of the pins and held in place by set-screws 34^a. The arms 31 have annular bosses 35 36, 90 between which is an annular recess, in which the annular flange 38 of the roller 37 has bearing, the flange turning in this recess. The roller is supported and turns upon a hollow arbor, 39, having an oil-chamber, 40, closed at 95 bottom by a plug, 41, which screws into a recess of the roller 37. The arbor has oil-holes 42, leading from the oil-chamber to the bearing-surface between the arbor and the roller, and also an enlarged flange, 39^a, which bears 100 against a corresponding offset or shoulder formed on the interior of the roller 37.

43 is a screw, which is screw-threaded in the arbor 39, and whose head bears upon the top of the arm to hold the arbor in place.

44 is a cast, wrought, or steel ring, forming 5 the working-face of the roller 37, and held thereon by wedge or wedges 45, or in any suitable manner. Between the roller 37 and the ring 44 is an elastic cushion, 46. The cushion may be made of old rubber or leather belting.

10 It is customary to rely upon centrifugal force in this class of mills, but as the motion required to impart that force gives bad results by forming extreme counter-currents, holding the pulp high above the reducing-surfaces, and 15 wearing the screens with material not fine enough to pass through them, I have in wet work adopted slow motion, and to force the rollers against the die-ring use springs to assist the centrifugal force.

20 On top of the arms 31 are cast or otherwise fixed lugs 47 and 48, and in said lugs 47 are sockets 49, for the nut ends of rods 50.

25 51 is a saddle on lug 48, and through both saddle and lug is a hole to admit free movement of the rod 50, the socket 49 and the hole 52 being made flaring, as shown in section in Fig. II, to allow the uncramped working of the rod 50. At 53 are jam-nuts screwing on the rod 50.

30 54 are rubber springs, through which the rod 50 passes, the springs bearing at one end against the jam-nuts and at the other end against the saddle 51.

35 It will be seen that the effect of the springs is to force the free ends of the arms 31 asunder, and thus to force the rollers to the die-ring, each of the springs acting upon two of the arms. With this combination I secure capacity 40 for efficient work with moderate rotary speed. For dry work high speed is admissible, fifteen hundred feet per minute on the face of the die-ring giving better results than a slower motion, while for wet work the speed should not exceed five hundred feet per minute.

45 The springs may be of any material or construction, and may be arranged to act on the rollers by other systems of connections; but I prefer placing them in line with the roller centers, as it relieves the propelling mechanism from undue friction.

50 At 55 is one of the several ribs upon the bottom of the driving-disk, to which may be hinged drags (see dotted lines, Fig. VIII) that in dry work carry the material outward from the center to the die ring 29.

55 56 is a hood which is used on the mill in dry-pulverizing, the outer part resting on the wall 20. 57 is a marginal down-turned flange engaging the edge of the wall. The center of 60 the hood is open at 58 to admit the top of the hopper, the parts being out of contact as the hopper revolves, and the hood is stationary. There must be formed an air-joint between the hood and the hopper. For this purpose 65 the hopper is formed with an annular trough, 59, and the hood with an annular flange, 60, which dips down into the trough, so that when

the trough contains liquid, as shown, no air can pass through the orifice 58. The liquid preferred for this purpose is glycerine. On 70 the under side of the hood are radial tubes 61, with their outer ends open to the inside of the mill, while the inner ends of the tubes are closed to the inside of the mill and open to an annular chamber, 62, with which communicate 75 the two ends of a branch pipe, 63, that is in connection with the suction end of a fan or blower or vacuum-producing agent of any suitable kind. By this combination matter in the mill fine enough to move with a given current of air will pass from the inside of the mill to any chamber made to receive the same, the coarseness of the material which is carried off depending on the velocity of the air current. If the hood 56 is used, the screen orifices 23 80 are closed by sheet-iron 24. (See Fig. VIII.) This will make the mill close, so that no air will enter the mill except through the hollow legs of the hopper.

85 The general operation of the machine for 90 wet work is to introduce the ore and water into the hopper, from whence they pass into the machine. The action of the rollers rotates the mass, and each roller keeps up a counter-current, by which the fine material is kept in 95 suspension and the coarser material sinks to the bottom and there crumbles under the action of the rollers. The fine matter passes through the screens 24 into the annular hopper 21 and may be disposed of in any manner. 100

In working dry ore sheet-iron 24 (see Fig. VIII) is put in place of the screens and the air-hood put on and the couplings made for air-draft. The fine material is carried by suction through the pipes 61, chamber 62, and branch 105 pipe 63, as before set forth.

The part numbered 12 is throughout this specification called a "working disk," but it will be observed that it is not a disk, strictly speaking—that is to say, it is mutilated or cut 110 away for the passage of the vertical axes or hubs of the crushing-rollers, so that the portions which are left constitute nothing more nor less than "arms," the width of which will vary according to the extent to which the disk 115 is cut away. It is only necessary that enough of the disk should be retained to afford a bearing to the parts.

I claim—

1. The combination, with the crushing-roller 120 37, having a central perforation and an offset or shoulder, substantially as described, of the arm 31, having a perforation, 33, a hollow arbor, 39, having the perforations 42 and the enlarged flange, the screw 43, engaging said arbor and having the enlarged head bearing upon the arm 31, and the plug 41, closing the lower end of the perforation through the roller, as and for the purpose set forth.

2. The combination, with the perforated 130 arm 31, having the downwardly-projecting bosses 35 and 36, forming an annular groove between them, of the crushing-roller 37, having the bearing-flange 38 occupying said an-

nular groove, the central perforation and the offset or shoulder, the arbor 39, having the enlarged flange engaging said offset or shoulder, and the screw 43, supporting said arbor, 5 as set forth.

3. The combination, with the perforated arm 31 and the crushing-roller having a central perforation, of the arbor 39, open from end to end and having the perforations 42, and 10 the plugs 41 and 43, closing the respective ends of the arbor 39, substantially as set forth.

4. The combination, with the casing and the horizontal die-ring 29, of the horizontal disk 12, the arm 31, hinged upon a vertical axis to 15 said disk, and the crushing-roller 37, having a vertical axis projecting downwardly from the under side of said arm 31, substantially as set forth.

5. The combination with the casing, horizontal die-ring, and the crushing-roller having a vertical axis, of the horizontal working-disk having the cut-away portion for the passage of 20 said vertical axis, and the arm carrying the axis of the crushing-roll, hinged upon a vertical axis to the upper side of said disk, as set forth.

6. The combination, with the casing, die-ring, horizontal working-disk 12, and the arm 31, hinged thereto upon a vertical axis, of the 25 crushing-roller 37, its axis projecting perpendicularly from the under side of said arm 31, and a spring exerting its force outwardly against said arm, as set forth.

7. The combination, with the casing, die-ring, the working-disk, a plurality of arms hinged thereto, and the crushing-rollers, of a 30 spring engaging at its respective ends with two of said arms, whereby the crushing-rollers are forced outwardly, as set forth.

8. The combination, with the casing, die-ring, horizontal working-disk, a plurality of arms hinged thereto upon vertical axes, and the crushing-rollers having vertical axes carried by said arms, of springs, each engaging 45 at its respective ends with two of said arms, whereby their free extremities are moved outwardly, as set forth.

9. The combination, with the casing, die-ring, horizontal working-disk, a series of 50 arms (more than two) hinged thereto, and the crushing-rollers, of springs, each bearing at its respective extremities against the two adjacent arms, whereby all of the arms of the series are connected and the tension of all of 55 the springs equalized, substantially as set forth.

10. In an ore-crusher substantially as herein described, the combination, with the casing, the die-ring, the working-disk 12, the arms 31, hinged thereto, and the crushing-rollers carried by said arms, of the rod 50, bearing at one extremity against one of said arms, and the compression-spring 54, surrounding and bearing at one end against said rod, and at the other against another of the 60 arms, 31, substantially as set forth.

11. The combination, with the casing, the

die-ring, the disk 12, the arms 31, hinged thereto, and the crushing-rollers carried by said arms, of the lug 47 on one of said arms, and the lug 48 on the other, the rod 50, extending from one of said lugs to the other, and the compression-spring 54, surrounding 70 said rod and pressing in opposite directions against said lugs, substantially as set forth.

12. The combination, with the casing, the die-ring, the working-disk, and the arms 31, hinged thereto, of the lug 47 on one of said arms, having the socket 49, the lug 48 on the other of said arms, having the perforation 52, the rod 50, passing through said perforation 80 and bearing at one extremity in said socket, the nut 53 on said rod, and the spring 54, surrounding said rod, and bearing at its respective extremities against said nut 53, and lug 48, as and for the purposes set forth. 85

13. In an ore-crusher substantially as herein described, the combination, with the casing, the die-ring, the crushing-rollers, the working-disk, and the hopper carried thereby, of the trough carried by said hopper, 90 the liquid contained in said trough, the hood having a central aperture for the passage of said hopper, and the flange dipping into said liquid, and an exhaust-pipe communicating with the interior of the machine. 95

14. In an ore-crusher substantially as herein described, the combination, with the casing, of a hood covering the top thereof and having an aperture therethrough, a hopper-spout projecting through said aperture, and a liquid seal between said hopper-spout and hood, substantially as set forth. 100

15. In an ore-crusher, the combination, with the machine, a hood covering the same, a hopper projecting through said hood, and a liquid joint between said hood and hopper, of the branch pipes 61, communicating with the machine beneath the hood, the annular chamber 62, with which said pipes communicate, and the exhaust-pipe 63, communicating with said chamber 62, substantially as set forth. 110

16. The combination, with the casing, die-ring, and base-plate having the raised and perforated center, substantially as described, 115 of the working-disk bearing upon said raised center, the crushing-rollers carried by said disk, and the working-shaft extending through said perforation and carrying said disk, substantially as set forth. 120

17. The combination, with the casing, die-ring, the base-plate having the raised center, the working-disk bearing thereon, and the crushing-rollers carried by said disk, of the annular flange extending downward from the 125 under side of the working-disk and surrounding the raised portion of the base, for the purposes set forth.

ALBION M. ROUSE.

In presence of—

EDMUND J. BÖRDEN,
ALBION E. ROUSE.
